CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

METHOD AND APPARATUS FOR THE RECTIFICATION OF ALTERNATING CURRENTS.

Application filed October 8, 1920. Serial No. 415,536.

The present invention relates to a method and apparatus for the rectification of alternating currents. 55

In my copending Patent No. 1,545,207 granted July 7, 1925, I have disclosed a new form of insulating gap for preventing conduction through a gas. According to this disclosure, the surfaces of the electrodes immersed in the gas are located in close proximity to normally prevent a sufficient number of collisions between electrons and atoms to initiate gaseous conduction. As explained therein, this result is accomplished by spacing the active surfaces of the electrodes 10 at different potentials a distance apart which is relatively short and of the order of magnitude of the mean free path of the electrons. 60

I have discovered in connection with an apparatus of this character that it is possible to render the gap between electrodes, substantially freely conducting in one direction and nonconducting up to voltages which will actually destroy the tube in the opposite direction. 65

In the simplest and most efficient embodiment of the invention which has yet been devised asymmetric electrodes are employed in conjunction with a constant magnetic field. Although this magnetic field should be constant yet it is found that between certain critical limits the tube is conducting in a direction which renders the outer electrode negative and nonconducting in the opposite direction. 70

Although the critical limits of field strength are not accurately determined, it is known that for a certain magnetic field strength above a minimum value the tube is conducting in one direction only up to a certain higher critical value at which the tube conducts freely in both directions. 75

In the specific embodiment of the invention disclosed comprising concentric cylinders of different diameters it has been determined that the critical field strength at which the tube becomes conducting in both directions bears a certain definite relation to the minimum value of field strength at which the tube rectifies which is proportional to the diameters of the inner and outer cylinders. 80

In one embodiment of the invention in which the diameters of the inner and outer cylinders were as one to two, the same relation prevailed between the lower and upper limits of field strength bounding the region in which the tube was conducting in one direction only. 85

It is believed that the theory underlying this mode of operation of the tube is somewhat as follows: Owing to the magnetic field, electrons leaving the outer or larger cylinder are caused to describe curves without coming immediately into contact with the inner cylinder, thus affording opportunity for collision, whereas the paths of electrons leaving the inner cylinder are not distorted or are distorted insufficiently to prevent these electrons from immediately reaching the outer cylinder. They therefore reach the outer cylinder after having traversed only a short path. According to this theory, gaseous conduction is permitted in a direction which makes the outer cylinder negative. 90

The advantages of this construction when employed as a rectifier of high voltages are manifold as a large amount of energy may be transmitted through a gaseous medium by ionic conduction and the voltage drop through the tube for potentials of the order of ten thousand volts or greater is negligible. Further more the tube is not injured by short circuits of short duration. 95

One feature of the invention accordingly contemplates the use of two electrodes immersed in a gas and having similarly curved surfaces together with means for creating a magnetic field of constant strength in the space between the electrodes to cause the tube to conduct freely in one direction and insulate in the opposite direction. 100

A further feature of the invention contemplates the employment of asymmetric electrodes immersed in gas together with a constant magnetic field extending substantially axially of the electrodes. 105

In the accompanying drawings illustrating the preferred form of the invention Fig. 1 represents a section in elevation of a tube adapted to act as a rectifier of high voltages; and Fig. 2 represents a typical circuit in which the rectifier tube may be embodied. 110

Upon referring to the illustrated embodiment of the invention as shown in Fig. 1 it will be observed that a sealed enclosing vessel 10 has contained therein two concentric electrodes 12 and 13 which are constructed of non-magnetic material such as

5 molybdenum. The opposite surfaces of the two electrodes are subjected to a potential difference and when the tube is operating conduction takes place in one direction in the space separating these surfaces. The 10 active surfaces of the electrodes are located in sufficiently close proximity to normally prevent gaseous conduction through the space separating them even under excessively high potentials (the gas preferably being rarefied), as described in my copending patent hereinbefore referred to. By interposing a constant magnetic field with 15 lines of force extending substantially parallel to the axes of the electrodes, the tube is made conducting in one direction and insulating in the opposite direction. This magnetic field may be created by a permanent magnet 15 located with respect to the tube 20 as shown in Fig. 1. Cooperating with the permanent magnet are tubes or cylinders 17 and 18 of magnetic material which engage with opposite ends of the electrode cylinder 13 and serve to localize the magnetic field 25 in the region between the electrodes 12 and 13. The two cylinders 17 and 18 are clamped to the electrode cylinder 13 and to one another through a sleeve 19 of non-magnetic material. It will be observed that 30 the outer electrode 13 consists of a thin metallic cylinder having its opposite ends received in grooves formed in the adjacent faces of the cylinders 17 and 18. In order to permit the free escape of heat from the 35 region surrounding the outer electrode 13, the connector sleeve 19 is preferably provided with openings or slots 14 as indicated in the drawings. The inner electrode 12 is connected at its opposite ends with 40 iron rods 20 and 21, the rod 20 having a head 22 formed thereon and the rod 21 having its end threaded at 23. The electrode is preferably fused or welded to the rods to form a continuous rod having its central 45 section of non-magnetic material. Surrounding the outer ends of the rods 20 and 21 are insulating cylinders 24 and 25 of glass or similar material which are seated in recesses 26 formed respectively in the cylinders 17 and 18. The insulating cylinders 50 may be held in place by collars 27 and 28 of copper or other non-magnetic material, each having a neck 29 which projects into the space between the rods 20 and 21 and the surrounding cylinders 24 and 25. The 55 several elements are retained in assembled relation through the provision of a nut 30 engaging with the threaded end 23 and serving to draw the collars 27 and 28 against the ends of the cylinders 24 and 25. In 60 order to insure that all paths through the supporting dielectric subjected to a potential gradient shall be long and that all paths through the gas shall be short the outer 65 ends of the cylinders 17 and 18 are counter-

bored at 31 to separate the point of contact between the metal and insulating cylinders a substantial distance from the collars 27 and 28 which are in contact with the rods 20 and 21. In addition the collars are each 70 provided with an annular flange 33 extending parallel but spaced away from the walls of the enclosing vessel. From an inspection of the drawings, it will be observed that the outer cylinders do not contact directly with 75 the enclosing vessel but are centered within the vessel and spaced away from the walls by rings or washers 35. One of the leading-in wires 36 may be conveniently connected with the head 22, passing outwardly through 80 the end of the tube and the other wire 37 may be connected with the sleeve 19 passing outwardly through the side of the tube at 38.

From the foregoing it will be evident that 85 gaseous conduction around the boundary of the space between the cathode 13 and anode 12, that is from the anode around the end of the cylindrical space between cathode and anode to the outside of the cathode, is obstructed by the pole pieces 17 and 18. While 90 each pole piece is spaced from the anode this space is comparable to the mean free path of electrons in the gas (being somewhat less than the spacing between cathode and anode) and therefore just as effective to 95 obstruct conduction as if the gap were wholly closed as between the cathode and pole pieces.

It will also be evident that the space between the cathode and anode is rendered 100 alternately conducting and non-conducting as a result of variations in the state of ionization of the gas in the space, these variations being effected in the illustrated embodiment by periodic changes in the relationship between the electric and magnetic fields; that is, while one of the fields (the magnetic field) is constant the other field (the electric field) varies, both in intensity 105 and direction, at the frequency of the alternating field impressed upon the electrodes. Thus the discharge path is selectively controlled in accordance with the instantaneous polarity of the electrodes; when the cathode 110 is negative current flows whereas when the anode is negative little if any current flows. Obviously this invention is particularly applicable to glow-discharge tubes in contradistinction to arcing tubes.

The voltage drop through the tube even 115 when employing air approximates only about 300 volts which is negligible when voltages of the order of 10,000 volts or greater are being rectified. It should be understood in this connection however, that 120 inasmuch as the voltage drop through the tube approximates at the most about 300 volts, the apparatus may probably be used to advantage in the rectification of alternating currents where a potential of 500 volts 130

or even less is employed. By using helium or a similar gas within the enclosing vessel, this voltage drop through the tube is greatly reduced, the use of such a gas cutting the 5 voltage drop practically in half. In addition the use of helium is advantageous as it has a small molecule and in consequence a long mean free path which permits the use of an operating pressure for the gas 10 considerably greater than the practical operating pressure for air.

Although the exact field strength for different types and dimensions of tubes has not been accurately determined, it is known that 15 in one case a field strength of two hundred gauss caused the tube to rectify potentials as high as 20,000 volts and that a decrease of twenty-five gauss caused the tube to become insulating.

20 In the circuit diagram shown in Fig. 2, an input circuit is indicated at 40 capable of delivering alternating current at 110 volts to the primary of a step-up transformer 42. The secondary of this transformer is embodied in an output circuit 43 containing the tube which rectifies the high voltage alternating current delivered thereto by the secondary of the transformer. The output circuit obviously may be connected with any 25 desired form of load circuit (not shown) to utilize the high voltage current so rectified.

It will be obvious to those skilled in the art that the rectifier tube, if so desired, may be made with two parts to rectify both 30 halves of the alternating current wave, thus increasing the applicability of the tube. This form of tube may be advantageously employed in the production of high voltage direct current for X-ray apparatus, electrical precipitation of suspended particles by the Cottrell process, railway electrification, and other purposes where stationary rectifiers or rotary converters are now employed.

From the foregoing it will be evident that 35 the sleeve 25 of insulating material, which surrounds the conductor 20 to electrode 12 between this conductor and the conductor 18 which contacts with electrode 13, as well as the thin metallic cup-shaped plate 27, which extends from the end of the sleeve 25 outwardly to the region of the surrounding tube, serves to restrain gaseous conduction between said conductors and to confine the electrical discharge to the interior of the 40 hollow electrode. Insulating sleeve 24 and cupped plate 28 perform similar functions at the upper end of the tube.

By virtue of the narrow space between conductor 20 the member 18 (also 21 and 45 17), which spacing is less than the mean free path of electrons in the gas, and the insulating ring 25 (also 24), which is similarly spaced from the conductor, and the plate 27 (also 28), which is similarly spaced from the 50 tube wall, the gaseous discharge between the

electrodes 12 and 13 is effectually confined to the space between the opposed surfaces of the electrodes notwithstanding the tendency of such a discharge to jump to the point where a conductor passes into a body 70 of insulation. By enclosing the discharge in a chamber within the tube (formed in this case by parts 13, 17, 18, 24, 25, 27, 28, etc.) the discharge is protected from outside influences such as accumulated charge on 75 the wall of the tube or elsewhere, and the tube is protected from deleterious effects of the discharge such as interaction between the gas and the glass when radiation from the discharge reaches the region of the tube 80 wall as in prior devices.

In the particular embodiment of the invention illustrated in the drawing, the means additional to the space charge (charged particles) for selectively causing 85 electrons passing in different directions through the gas to take paths of widely different lengths comprises the magnetic field.

In a generic sense the term hollow cathode 90 includes a cathode whose active surface only partially surrounds a gaseous medium so that the medium immediately adjacent the active surface is more or less pocketed or confined.

I claim—

1. A method of controlling the flow of electric currents through a gas filled space which consists in positioning two electrodes with their opposing surfaces in such close proximity as to normally prevent conduction 100 through the space, and lengthening the paths of electrons coming from one of the electrodes sufficiently to cause gaseous conduction in one direction through the space.

2. An electrical apparatus comprising concentric electrodes of non-magnetic material, a gas filled vessel enclosing the electrodes, cylinders of magnetic material positioned at opposite ends of the outer electrode, and means for interposing a magnetic field in 105 the space separating the electrodes, the region of which is determined by the cylinders of magnetic material.

3. An electrical apparatus comprising asymmetric electrodes immersed in a gas with a space therebetween comparable to the mean free path of electrons in the gas, and means for causing gaseous ionization and conduction for electrical potentials in one direction only between the electrodes. 115

4. An electrical apparatus comprising concentric electrodes of non-magnetic material, positioning members of magnetic material engaging with opposite ends of the electrodes, means for holding the parts in assembled relation and a gas filled vessel enclosing the electrodes and retaining members. 125

5. A rectifier comprising a gas filled receptacle, means for creating an electric field in a portion of the gaseous region within 130

- the receptacle, means for limiting the flights of electrons through the gas in one direction of applied electric field to distances which are short and comparable to the mean free 5 path of electrons in the gas, and means whereby electrons impelled by a field in the reverse direction take paths sufficiently long to cause gaseous ionization and conduction.
6. An electrical apparatus comprising a 10 gas filled tube, inner and outer cylindrical electrodes received within the tube and located with their axes substantially coincident, means for creating an electric field in the space separating the inner and outer 15 electrodes, cylinders of magnetic material positioned concentric with the electrodes, and means cooperating with the cylinders of magnetic material for introducing a magnetic field into the annular space separating 20 the electrodes.
7. In a rectifier, a vacuum tube, a hollow cathode and an anode arranged opposite thereto at a distance less than the mean free 25 path required for ionization under electro-motive forces impressed in one direction.
8. The method of rectifying alternating 30 current which comprises impressing an alternating electric field in a gas space which is sufficiently short and in which the gas pressure is sufficiently low to prevent initiation 35 of substantial conduction directly across said space in one direction by a field strong enough to initiate conduction across longer spaces, and causing gaseous ionization and conduction to take place in the opposite direction in response to said alternating electric field.
9. The method of rectifying alternating 40 current which comprises impressing an alternating electric field in a gas space which is sufficiently short and in which the gas pressure is sufficiently low to prevent initiation 45 of substantial conduction directly across said space in one direction by a field strong enough to initiate conduction across longer spaces, causing gaseous ionization and conduction to take place in the opposite direction in response to said alternating electric field, and obstructing gaseous conduction 50 around the boundary of said space.
10. A gaseous conduction device comprising a hollow cathode, an anode presented to the interior surface of the hollow cathode, and a metallic obstruction for preventing 55 discharge from the anode to the outside of the cathode, the obstruction being spaced sufficiently close to one of the electrodes to prevent substantial ionization in the space by electrons passing across the space.
11. A gaseous conduction device comprising a hollow cathode, and means to control the rate of electron emission from the cathode by varying the state of ionization of the gas inside the hollow cathode.
12. A gaseous conduction device compris- 60 65 70 75 80 85 90 95 100 105 110 115 120 125 130
- ing a hollow cathode, and means to vary electron emission from the inner surface of the cathode by recurrently ionizing the gas in the hollow cathode at a predetermined frequency.
13. The method of producing pulsating gaseous conduction between two electrodes with a gas space therebetween sufficiently short normally to prevent conduction therebetween, which comprises concomitantly impressing electric and magnetic fields upon the space between the electrodes and periodically varying the relationship between the fields to vary the conductivity of the gas in the space.
14. The method of producing pulsating gaseous conduction between two electrodes with a gas space therebetween sufficiently short normally to prevent conduction, which comprises impressing an electric field between the electrodes and selectively controlling the discharge path depending upon the instantaneous polarity of the electrodes.
15. A gaseous conduction device comprising a hollow cathode, an anode presented to the interior surface of the cathode, means for producing discharge between the anode and the interior surface of the cathode, and means for preventing discharge between the anode and the exterior of the cathode.
16. Electrical apparatus comprising opposed electrodes having therebetween a gas space sufficiently short to prevent substantial ionization by electrons traveling directly across the space and means permitting electrons to follow longer paths in one direction of applied potential between the electrodes to initiate gaseous conduction without initiating substantial conduction when the same potential is applied in the opposite direction.
17. An electrical discharge tube containing a hollow electrode, a conductor extending through the wall of the tube, an electrode surface presented to the interior of said hollow electrode and receiving current through said conductor, and a metallic member surrounding said conductor intermediate said surface and that part of said wall through which said conductor extends, said member extending from the region of said conductor to the region of said wall.
18. An electrical discharge tube containing a hollow electrode, a conductor extending through the wall of the tube, an electrode surface presented to the interior of said hollow electrode and receiving current through said conductor, an insulating sleeve surrounding said conductor intermediate said surface and that part of said wall through which said conductor extends, and a metallic member surrounding said conductor intermediate said sleeve and said part of the tube wall.
19. Electrical discharge apparatus com-

- prising electrodes separated by a gaseous medium, means for permitting a discharge between the electrodes through the gaseous medium and means for confining the discharge to the electrodes, including surfaces spaced apart a distance which while appreciable is substantially confined to the mean free path of the electrons in the gas. 65
- 5 20. An electrical discharge tube having interior electrode surfaces presented to each other across an intervening space, a conductor extending through the wall of the tube for conducting current to one of said surfaces, and a metallic member surrounding said conductor intermediate said surfaces and that part of the tube wall through which said conductor extends, said member being in non-conducting relation to said one surface. 70
- 10 21. Electrical discharge apparatus comprising electrodes separated by a gaseous medium, means for permitting a discharge between the electrodes through the gaseous medium, and means for confining the discharge to the electrodes, including surfaces spaced apart a distance which while appreciable is substantially confined to the mean free path of electrons in the gas, one of the surfaces being insulating. 75
- 15 22. An electrical discharge tube containing a hollow electrode having an opening in one end, an electrode surface presented to the interior of said hollow electrode, a conductor passing through the wall of the tube for conducting current to said surface, a second conductor in conducting relation to said hollow electrode, and a sleeve of insulating material surrounding the first conductor with an outer peripheral surface between the two conductors. 80
- 20 23. An electrical discharge tube containing electrodes separated by a gaseous medium, means permitting gaseous discharge between the electrodes, and means presented to the surface of one of the electrodes throughout the entire circumference thereof, with a surface opposed thereto across a space which while appreciable is substantially confined to the mean free path of electrons in the gaseous medium, whereby the electrical discharge is confined to the area of the latter electrode which is presented to the other electrode. 85
- 25 24. An electrical discharge tube containing an electrode having an extensive discharge surface, a smaller active surface presented to said discharge surface across a gas space, a conductor extending through the wall of said tube for conducting current to said active surface, and an annular member surrounding said conductor intermediate said active surface and said wall with a surface opposed thereto across a space which while appreciable is sufficiently short to prevent the discharge from passing thereto. 90
- 30 25. An electrical discharge tube containing an electrode having an extensive discharge surface, a smaller active surface presented to said discharge surface across a gas space, a conductor extending through the wall of said tube for conducting current to said active surface, and an annular metallic member surrounding said conductor adjacent said active surface with a surface opposed thereto across a space which while appreciable is sufficiently short to prevent the discharge from passing thereto. 95
- 35 26. An electrical discharge tube containing an electrode having an extensive discharge surface, a smaller active surface presented to said discharge surface across a gas space, a conductor extending through the wall of said tube for conducting current to said active surface, and means for confining the discharge to said active surface including a ring of insulation surrounding said conductor, said ring having a surface opposed to the conductor across a space which while appreciable is sufficiently short to prevent the discharge from passing thereto. 100
- 40 27. Electrical discharge apparatus comprising a tube containing electrode surfaces separated by gaseous medium, and means for shielding the entire wall of the tube from light radiation emanating from the electrical discharge between said surfaces, said means including a chamber surrounding said surfaces, an interior face of said chamber constituting one of said electrode surfaces. 105
- 45 28. A gaseous conduction rectifier comprising a gas filled receptacle, a pair of electrodes received in the receptacle, means for permitting the formation of a positive space charge adjacent one of the electrodes, and means additional to the space charge for selectively causing electrons passing in opposite directions between the electrodes, by virtue of alternating potential applied to the electrodes, to take paths of widely different lengths. 110
- 50 29. A gaseous conduction rectifier comprising two electrodes having surfaces of different areas presented to each other, means for preventing substantial discharge between the electrodes, during the half-cycles of applied alternating potential when the smaller surface is negative, including a gas filled gap sufficiently short normally to prevent gaseous conduction thereacross, and means whereby the electrons coming from the larger surface, during alternate half-cycles of applied alternating potential when the latter surface is negative, take paths sufficiently long to cause gaseous conduction during said alternate half-cycles. 115
